UNITED STATES PATENT OFFICE.

GEORG ERDMANN, OF BERLIN, AND CLARA FISCHER, OF CHARLOTTENBURG, GERMANY,
GUARDIAN OF GOTTHOLD FISCHER, AN INSANE PERSON.

DEVICE FOR PREVENTING COLLISIONS AT SEA.

No. 914,483.

Specification of Letters Patent.

Patented March 9, 1909.

Application filed October 21, 1907. Serial No. 398,522.

To all whom it may concern:

Be it known that we, GEORG ERDMANN and GOTTHOLD FISCHER, insane, (CLARA FISCHER, guardian,) subjects of the German Emperor, residing at Berlin and Charlottenburg, respectively, both in Germany, have invented certain new and useful Improvements in Devices for Preventing Collisions at Sea, of which the following is a 10 specification.

The purpose of this invention is to provide improved apparatus for automatically preventing the collision of ships at sea and thereby obviating the dangers attending 15 navigation in foggy weather and by night. Entirely automatic action of apparatus used for this purpose has hitherto only been obtained by using purely mechanical devices, namely by utilizing, for the actuation of the 20 apparatus, the shocks produced by the impact of solid bodies carried by the ships. These known mechanical devices are extremely complicated and expensive and also have the disadvantage that they only protect the ships from the dangers of collisions 25 threatened at certain parts where the "feelers" provided for the reception of the shocks or impact are arranged.

For preventing collisions of railway trains, 30 that is to say of vehicles which are confined to traveling on rails in certain predetermined directions, it has already been proposed to use apparatus adapted to be actuated by electric waves of predetermined length and 35 frequency, so that certain transmitters on trains traveling in one direction are tuned to co-act with certain receivers on trains traveling in the opposite direction. Since ships are not confined to exactly predetermined 40 paths or courses arrangements of this kind are unsuitable for sea traffic. The devices hitherto known for protecting sea traffic in fogs or by night, so far as they depend upon the action of electric waves, are exclusively 45 used for producing signals, and since there is no guarantee that the signals will be heeded in time to prevent accidents, these known devices do not afford sufficient security.

The present invention utilizes the fact, 50 that the operative effect of electric waves can be limited to the space within a circle of a certain radius having the transmitter at its center, for instance by regulating the

length of the sparks and the antennæ or sky-wires used.

The object of the invention is to automatically produce the stoppage of the ships as soon as they approach the danger zone, that is to say as soon as they reach the limit of 60 the zone of safety. For this purpose the apparatus used for producing the electric waves is made to co-act with apparatus for stopping the engines of the ships.

Figures 1 and 2 show two installations, 65 complementary to each other, designed to be carried by the two ships traveling in predetermined directions. Figs. 3 and 4 illustrate the arrangement of two installations, 70 complementary to each other for protecting two ships traveling in arbitrary directions. Figs. 5 to 7 illustrate details of the apparatus.

In connection with signaling arrangements it is already known, to prevent the 75 actuation of a receiver by a transmitter on the same ship by causing the respective circuits to be alternately closed and interrupted by means of an automatic switch. If a similar arrangement were adopted on 80 both ships it might of course occur that the two automatic switches were acting synchronously, that is to say, that alternately both receivers and both transmitters were out of action, in which case the apparatus 85 would of course be inoperative. This possibility can however be avoided by causing the alternate make and break of the circuits to take place on only one of the ships, and keeping one circuit on the other ship normally open. An arrangement of this kind is shown in Figs. 1 and 2.

Fig. 1 shows an installation of an induction apparatus a^1 , the primary circuit 1^1 of which contains a weak battery b^1 and a normally open switch c^1 with means of automatically closing the latter; the secondary circuit 2^1 contains the transmitter d^1 .

The lever h^1 in Fig. 2 has in addition to the projection h^1_3 a projection h^1_5 located opposite a fixed contact H^1 . From this contact H^1_5 a wire 5^1 leads to an electro-magnet q , battery r and lever-bearing h^1_4 and thence to the contact h^1_5 . Opposite the electro-magnet q is an armature lever S , which is fixed to the 100 pivoted switch lever c^1 . When the coherer e^1 becomes conductive the circuit 4^1 is closed for the purpose of producing actua-

tion of the rod p^1 connected to the throttle valve, and at the same time the circuit 5^1 is closed, so that the electro-magnet q attracts the armature s and closes the circuit 1^1 .
5 The transmitter d^1 then remains in action until the switch c^1 is opened again by hand.

The installation II (Fig. 1) on the other ship comprises in addition to a transmitter a coherer e^2 and an automatic switch. The 10 latter consists, in its most simple form of a rapidly rotating wheel t , having a segmental strip of metal t_1 fixed to its circumference, but otherwise not electrically conductive. This wheel is in contact with two pairs of 15 contact-springs u , arranged respectively in the circuit 2^2 of the transmitter and in the circuit 3^2 of the coherer e^2 . The two pairs of springs u are so arranged that they cannot be simultaneously in contact with 20 the contact strip t_1 .

In the installation II (Fig. 1) the receiver circuit and accessory parts are exactly similar to the corresponding parts in the installation I (Fig. 2), and in the drawing like letters and numerals are used to indicate the respective parts, but with the index "1" in Fig. 2 and the index "2" in Fig. 1.

With the apparatus shown in Fig. 2 the excitation of the magnet g^1 , which occurs 30 when the coherer e^1 is acted on by electric waves, not only causes the rod p^1 to be actuated to stop the engines of the ship carrying the installation I, but also causes the transmitter circuit 1^1 to be closed, so that the 35 transmitter d^1 acts on the coherer e^2 which produces the stoppage of the engines of the ship carrying the installation II by closing the circuit 3^2 which energizes the magnet g^2 , attracting h^2 , closing contact at h^2 , thus 40 closing circuit 4^2 , energizing 1^2 , attracting m^2 and causing p^2 to stop the engine. The continued working of the transmitter d^1 after the stopping of the engines of the ship by which it is carried not only serves to stop 45 the engines of the ship carrying the installation II, but also affords a safeguard against the approach of other ships provided with similar apparatus. For the same reason it is desirable that the transmitter d^2 should 50 also continue to work uninterruptedly. For this purpose the rotation of the wheel t is automatically stopped in a position in which it closes the circuit 2^2 of the transmitter d^2 . V is a lateral boss fixed to the wheel t and 55 provided with a single tooth V_1 ; W_1 is a lever fulcrumed at W_4 and connected to a spring Y so that its arm W_2 is normally held in contact with an abutment Z . The arm W_2 constitutes the armature of an electro- 60 magnet X , the coils of which form part of a circuit 6^2 which is closed at H^2 when the lever h^2 is rocked by the magnet g^2 . The arm W_1 of the lever W is adjacent the boss V , but when the lever is in its normal 65 position the tooth V_1 clears the said arm dur-

ing the rotation of the wheel t . When, however, the lever W is rocked by the action of the electro-magnet X the arm W_1 is moved into the path of the tooth and prevents further rotation of the wheel.

70

The apparatus shown in Figs. 1 and 2 has the disadvantage that the installations on the two ships are not exactly alike, and the desired effect is not produced, if two ships both provided with installations like that shown in Fig. 2 approach each other, since in that case neither of the transmitters is in action. On the other hand, in the case of the meeting of two ships carrying installations with ordinary automatic make and break switches in their receiver and transmitter circuits, it may be the two automatic switches are working synchronously. This latter danger may in practice be obviated by arranging that no two automatic switches have the same working-period, but even in that case the period of one switch may be a multiple of the period of the other switch, and one of the receivers may not be acted on during the periods when its circuit is closed. In view of this it is preferable to make the arrangement as shown in Figs. 4 and 5, in which both installations have automatic switches t^1 t^2 provided with automatic stopping mechanism similar to that shown in Fig. 1. The 90 switches c^1 and c^2 on the two ships are in this case both closed by hand at the setting in of foggy weather and the beginning of each night. With this arrangement the action of electric waves transmitted from either ship 95 to the receiver of the other ship causes the automatic switch on the latter to be stopped in a position in which it closes the transmitter circuit. Electric waves are therefore, continuously transmitted from the ship already stopped, and these waves act, of course, on the receiver of the ship still in motion.

100

A preferred form of construction of the automatic switch is illustrated in Figs. 5 to 110 7. On a plate A is mounted a spring-motor B connected by means of two toothed wheels C and D to a hollow shaft E of insulating material. To the shaft E are fixed four disks F , G , H , I insulated from each other with their 115 circumferences in contact with suitably supported springs K , L , M , N . The disk I consists of insulating material and has fixed to its circumference three segmental metal strips I^1 , I^2 , I^3 insulated from each other. 120 From these metal strips wires lead respectively to the metal-disks F and H and to a segmental metal-strip G^1 fixed to the circumference of the non-metallic disk G . The contact springs K , L , M are respectively connected to a terminal of the transmitter circuit, a terminal of the receiver circuit, and a terminal of the electric tapping apparatus 125 acting on the coherer. This tapping apparatus is not illustrated in the drawings. The 130

other terminals of these circuits are connected to the contact spring N. The segmental strips are so arranged relatively to each other that the circuits of the tapping apparatus, 5 receiver and transmitter are alternately closed in the order of succession in which they are here named. For additional security of insulation the spring L connected to the receiver slides on the non-conductive 10 surface of the disk G for a brief period before and after the transmitter circuit is closed.

What we claim as this invention and desire to secure by Letters Patent of the United States is:—

15 1. Apparatus for preventing collision at sea comprising in combination a self-acting transmitter of electric waves located on a collidable object, means for continuously operating said transmitter, a receiver for such 20 waves located on another collidable object being a ship, an electric circuit adapted to be closed by the action of said waves on the receiver, mechanism actuated by current flowing through the receiver circuit for stopping 25 the engines of the ship, a second transmitter of electric waves located on the ship, and an automatic make and break switch controlled by the receiving circuit, adapted to alternately break the receiver circuit and second 30 transmitter circuit.

2. Apparatus for preventing collision at sea comprising in combination a self-acting transmitter of electric waves located on a collidable object, means for continuously operating said transmitter, a receiver for such 35 waves located on another collidable object being a ship, an electric circuit adapted to be closed by the action of said waves on the receiver, mechanism actuated by current flow-

ing through the receiver circuit for stopping 40 the engines of the ship, a second transmitter of electric waves located on the ship, an automatic make and break switch adapted to alternately break the receiver circuit and second 45 transmitter circuit, and means actuated by the receiver circuit for locking said switch in the position in which it closes the second transmitter circuit.

3. Apparatus for preventing collisions at sea comprising in combination a transmitter 50 of electric waves located on one collidable object, a receiver for such waves located on the other collidable object, an electric circuit adapted to be closed by the action of said waves on the receiver, mechanism actuated 55 by current flowing through the receiver circuit for stopping the engines of a ship, a second transmitter of electric waves located on the last mentioned collidable object, and an automatic make and break switch adapted 60 to alternately break the receiver circuit and second transmitter circuit, said switch comprising a stationary contact, a rotatory disk, segmental contact strips on said disk adapted to successively slide on said stationary contact, conductive connections between said strips and terminals of one sign of the receiver and second transmitter circuits, and conductive connections between the stationary contact and terminals of the other sign of 65 said circuits.

In witness whereof we have signed this specification in the presence of two witnesses.
